TENNIS RACKET WITH CAPTIVE BALL APPARATUS

Rudolph Heinrich Heimers, Friedrich Otoman Heimers, and Siegfried Immanuel Heimers, all of 2001 Main St., Chula Vista, Calif.

Filed Sept. 16, 1957, Ser. No. 684,188

4 Claims. (Cl. 273—97)

The present invention relates generally to game apparatus and more particularly to a tennis racket with captive ball apparatus. This application is a continuation-in-part of our co-pending application, Serial No. 385,532, filed October 12, 1953, now Patent No. 2,806,700.

The primary object of this invention is to provide a tennis racket having a multiple pulley system mounted thereon on which is stored a considerable length of elastic cord, so that a ball attached to the elastic cord can be driven for a considerable distance, even the full length of a tennis court, and returned by the elastic cord.

Another object of this invention is to provide a captive ball apparatus having means for controlling the elastic cord, during extension, and means for storing surplus elastic cord.

Another object of this invention is to provide a tennis racket on which the pulley system is mounted so that, with the captive ball itself detached, the racket may be used for a normal tennis racket.

Another object of this invention is to provide a tennis racket on which the pulley system may be opened to facilitate loading the elastic cord.

Another object of this invention is to provide a captive ball apparatus which can be attached to any type of tennis racket without damage or alteration to the racket.

Another object of this invention is to provide a captive ball apparatus which is adapted for fabrication from many different materials, so that the choice of material can be according to the dictates of availability and price considerations, the exact sizes and proportions being matters easily determined to suit particular conditions and needs.

Another object of this invention is to provide a captive ball apparatus which is practicable and inexpensive to manufacture.

Finally, it is an object of this invention to provide a captive ball apparatus of the aforementioned character which is simple and convenient to use and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawings which form a material part of this disclosure, and in which:

Figure 1 is a top plan view of the tennis racket and complete captive ball apparatus;

Figure 2 is an enlarged fragmentary sectional view taken on the line 2—2 of Figure 1;

Figure 3 is an enlarged fragmentary sectional view taken on the line 3—3 of Figure 1;

Figure 4 is a fragmentary side elevational view of the handle portion of the racket;

Figure 5 is an enlarged fragmentary sectional view taken on the line 5—5 of Figure 1;

Figure 6 is an enlarged sectional view taken on the line 6—6 of Figure 1;

2

Figure 7 is a fragmentary sectional view taken on the line 7—7 of Figure 3; and

Figure 8 is a fragmentary sectional view taken on the line 8—8 of Figure 2;

5 Similar characters of reference indicate similar or identical elements and portions throughout the specification and throughout the views of the drawings.

Referring now to the drawings in detail, the apparatus includes a tennis racket 10 of normal type, having a

10 frame 12 and a handle 14 on which is a hand grip 16. Secured to the frame 12 directly opposite the handle 14 is a bracket 18 having an offset portion 20 from which extends a platform 22, close to and parallel to the general plane of the strings 24 of the racket, as shown in Figure 2. The bracket 18 has laterally extending lugs 26 which rest on the face of the frame 12 and the offset portion 20 has further lugs 28 which rest against the inner surface of the frame, said bracket being held in place by bands 30 of adhesive tape or the like which are wrapped around the frame and over said lugs.

20 Mounted on the platform 22 is a plate-like support frame 32 having on both sides a plurality of retaining tabs 34 which are folded under the platform to hold said support frame in place. Extending upwardly from the 25 sides of the support frame 32 adjacent one end are two hinge tabs 36, while at the other end thereof are two similar alignment tabs 38. Mounted on the support frame 32 is a pulley block 40 which fits between the hinge tabs 36 and alignment tabs 38 and is pivotally 30 attached by means of a hinge pin 42 through both of said hinge tabs and the pulley block. The pulley block 40 comprises a plurality of spaced, parallel plates 44 interconnected at one end by a common transverse spacer member 46, said plates defining runways 48 therebetween 35 on both sides of the spacer member. The plates 44 have a common transverse bore 50 in which are disposed a plurality of freely rotatable grooved pulleys 52 having their grooves aligned with the runways 48, said pulleys being mounted on a shaft 54, one end of which 40 is journaled in the end plate 56 of the pulley block 40, the other end of said shaft being embedded in a cap 58 which fits into a socket 60 in the other end plate 62 of said block. The pulley block 40 is held in place by a generally U-shaped retaining clip 64 straddling 45 the block, one end of said clip being pivotally attached to a hinge bracket 66 integral with and extending from an end of the support frame 32, the free end 68 of said retaining clip having an aperture 70 which snaps over the protruding end 72 of the shaft 54 to lock the clip in 50 place.

Secured to the handle 14 at the upper end of the hand grip 16 is a saddle plate 74 having folded ends 76 shaped to fit the cross-sectional contours of the handle, so that said saddle plate rests firmly in place as shown in Figure 6. The saddle plate 74 has a large lug 78 extending from each side thereof and securing bands 80 are wrapped around the handle 14 and these lugs to hold said saddle plate in position. Mounted on the saddle plate 74 is a further support frame 32 carrying a pulley

60 block 40, the structure being identical to that described above except that the pulley block is reversed so that the spacer members 46 of both pulley blocks are disposed toward each other. Also, for convenience, it is preferred that both pulley blocks 40 are hinged toward 65 the same side of the racket 10.

As shown in Figure 6, each pulley block 40 may be swung outwardly after releasing the retaining clip 64, thus exposing the runways 48 on both sides and facilitating the winding of the elastic cord 82 around the pulleys 70 52 in adjacent loops. The pulley blocks 40 are each raised by a leaf spring 81 fixed at one end in the hinge bracket 66 and extending beneath the pulley block in a

shallow channel 83 in the plates 44. The length of the leaf spring 81 is such that, with the pulley block 40 in raised position, the end of the spring snaps upwardly against the lower face of the pulley block to lock it in upright position, as in Figure 6. For simplicity, the winding of the elastic cord 82 is commenced on one of the outer pulleys 52 of the pulley block 40 on the frame 12 and is continued around successive pulleys of alternate pulley blocks, so that the final strand 84 of the elastic cord is around the opposite outer pulley 52 of the pulley block on the handle 14, as in Figure 1. The beginning, or fixed end 86 of the elastic cord 82, passes through one folded end 76 of the saddle plate 74 and is attached to a simple, plate-like spool 88 removably mounted between a pair of clamp blocks 90 secured beneath the handle 14 by further securing bands 80. The clamp blocks 90 have notches 92 into which the arm portions 94 at each end of the spool 88 are fitted, said spool being sufficiently resilient to snap into place easily.

Secured to the frame 12 on top of the bracket 18 is a guide head 96 having therein a frame 98 containing two crossed pairs of spaced, parallel guide rollers 100 and 102, said rollers being in the outer portion of the guide head remote from the adjacent pulley block 40. The inner portion of the guide head 96 has a deep clearance recess 104 from which an aperture 106 opens to the guide rollers 100 and 102, as shown in Figures 2 and 8. The final strand 84 of the elastic cord 82 passes through the central runway 48 of the pulley block 40 adjacent the guide head 96 and is threaded through the aperture 106 and between the guide rollers 100 and 102. It should be noted that the aperture 106 and the guide roller assembly are offset from the plane of the axis of the pulleys 52 sufficiently that the final reach 84 is held clear of the elastic cord 82 around said pulleys, as shown in Figure 2, to prevent binding of the elastic cord. The free end 108 of the elastic cord 82 is attached to the ball 110 with sufficient slack so that the ball can be brought into striking position relative to the racket. The guide head 96 is fixed in place by means of lugs 112 extending therefrom to rest on the bracket 18 and further lugs 114 which extend along the outer face of the frame 12, said lugs being held beneath the securing bands 30, and the lugs all have outwardly turned ends 116 to prevent slippage of the guide head during play.

In order to provide some means of control over the extension of the elastic cord 82, a friction brake structure is mounted on the handle 14. This friction brake comprises a generally C-shaped pressure bar 118 having at one end an inwardly turned portion 120 which is journalled in a support tab 122 extending from the saddle plate 74. Integral with and extending normally from the turned portion 120 is a brake arm 124, which is aligned with and fits into the outer runway 48 in the pulley block 40 which contains the final strand 84, as shown in Figures 3 and 7. The other end of the pressure bar 118 has a return folded portion 126 which fits tightly into the folded end 76 of the saddle plate 74 remote from the brake arm 124. Thus the pressure bar 118 is disposed laterally across the handle 14 and is shaped to extend angularly outwardly therefrom. By pressing on the pressure bar 118 with the hand holding the racket, the brake arm is forced outwardly against the elastic cord 82, as shown in dash line in Figure 3, so jamming said elastic cord against the spacer member 46 and preventing further extension of the elastic cord.

Since the elastic cord 82 normally extends and retracts very rapidly, the pulley blocks 40 have means to prevent the elastic cord from jumping off the pulleys and outside of the pulley blocks. This means comprises raised restrictors 128 which are integral with the plates 44 remote from the spacer member 46, said restrictors being disposed in opposed pairs, as indicated in Figures 6 and 7.

It is understood that minor variation from the form of

the invention disclosed herein may be made without departure from the spirit and scope of the invention, and that the specification and drawings are to be considered as merely illustrative rather than limiting.

Having described our invention, what we claim as new and desire to secure by Letters Patent is:

1. Apparatus including a captive element, a pair of pulley blocks each comprising a plurality of parallel spaced opposed plates, a spacer member on which one end of each of said plates is fixed, a plurality of pulleys having grooves to receive a linear element, means for mounting said pulleys on said blocks for free rotation and with said grooves disposed between said plates, said plates having portions at the other ends thereof extending beyond the corresponding pulleys and extending in the direction of the other block and also extending on opposite sides of each block to define runways, a length of elastic cord wound serially around said pulleys in adjacent loops and extending through said runways, one end of said elastic cord being attached to said captive element, said means for mounting comprising an axis member on which said pulleys are mounted, and means for terminally mounting said axis member in fixed relation to said pulley block, means for holding said pulley blocks in spaced relation, and means for securing of the other end of said elastic cord; said means for holding said pulley blocks in spaced relation comprising a tennis racket having a frame and a handle, one of said pulley blocks being secured to said handle adjacent the end thereof remote from the frame and the other pulley block being secured to the frame at a point remote from said handle; and roller guide means secured to said frame adjacent to the pulley block on the frame, said guide means comprising a set of freely rotatable guide rollers defining an aperture for the elastic cord offset from the common plane of said pulley blocks to hold the inner portion of the free part of the elastic cord out of contact with the pulleys of the pulley block on the frame while it is being fed into and payed out from the pulley block on the handle.
2. Captive ball apparatus comprising: a tennis racket having a frame and a handle; a first pulley block on said frame, and a second pulley block on said handle; each of said pulley blocks having therein a plurality of freely rotatable pulleys having their axes in a common plane; a continuous length of elastic cord wound serially around said pulleys in adjacent loops; said elastic cord having a free end, and a ball attached to said free end; the other end of said elastic cord being in fixed relation to the racket; roller guide means mounted on said frame for guiding said cord; said roller guide means being offset from the plane of the axes of said pulleys, so that the inner portion of the free part of the elastic cord is held out of contact with one of said pulley blocks while it is being fed into and payed out from the other pulley block; each of said pulley blocks being mounted on a pivot at one end of each pulley block, on said frame, to swing outwardly from said tennis racket; and means for retaining said blocks in operative position.
3. Captive ball apparatus comprising: a tennis racket having a frame and a handle; a first pulley block on said frame, and a second pulley block on said handle; each of said pulley blocks having therein a plurality of freely rotatable pulleys having their axes in a common plane; a continuous length of elastic cord wound serially around said pulleys in adjacent loops; said elastic cord having a free end, and a ball attached to said free end; the other end of said elastic cord being in fixed relation to the racket; roller guide means mounted on said frame for guiding said cord; said roller guide means being offset from the plane of the axes of said pulleys, so that the inner portion of the free part of the elastic cord is held out of contact with one of said pulley blocks while it is being fed into and payed out from the other pulley block; each of said pulley blocks being pivotally mounted

at one end to swing outwardly from said tennis racket; means for retaining said blocks in operative position; a spring operatively mounted at each of said pulley blocks and biasing said pulley blocks to swing outwardly from the tennis racket into upright position; each said spring also locking the corresponding pulley block in said upright position.

4. Captive ball apparatus comprising: a tennis racket having a frame and a handle; a first pulley block fixed to said frame, and a second pulley block fixed to said handle; each of said pulley blocks having therein a plurality of freely rotatable pulleys; a continuous length of elastic cord wound serially around said pulleys in adjacent loops; said elastic cord having a free end, and a ball attached to said free end; the other end of said elastic cord being in fixed relation to the racket; roller guide means mounted on said frame for guiding said cord; said roller guide means being offset from the plane of the axes of said pulleys, so that the inner portion of the

free part of the elastic cord is held out of contact with one of said pulley blocks while it is being fed into and payed out from the other pulley block; and friction brake means comprising a manually operated pressure bar pivotally mounted on one of said pulley blocks and having a brake arm integral with said pressure bar and longitudinally aligned with a part of said inner portion of the free part of said elastic cord and frictionally engageable therewith when pressure is applied to said pressure bar.
